UNITED STATES PATENT OFFICE.

ANTON JONCHA, OF MAYWOOD, ILLINOIS, ASSIGNOR TO OIL PRODUCTS APPLIANCE CO., OF MAYWOOD, ILLINOIS, A CORPORATION OF ILLINOIS.

FILL CAP.

Application filed January 18, 1928. Serial No. 247,642.

The invention is an improvement in caps for filling tubes of tanks such as employed by the usual filling station.

It is customary to furnish the filling station 5 with free equipment, including a large capacity tank, usually buried in the ground, and with pumps, the consideration being the exclusive right to supply the demands of the tank or tanks so installed. The tanks are 10 charged through filling tubes provided with removable caps and unscrupulous dealers have been known to take advantage of this in order to substitute a cheaper and inferior product to the manifest damage to the business 15 and good will of the producer. With the view of overcoming this dishonest practice, it is now the custom to provide a lock for the cap. Locked filling caps suffer the disadvantage that they must be constructed to permit 20 the use of a gauge rod and under some circumstances the opening for the passage of the gauge rod has been used to introduce inferior materials into the tank. Furthermore, the cap is carried by a sleeve section threaded 25 onto the filling tube and, as the sleeve can be disconnected from the tank, notwithstanding the locked cap, to open the filling tube, it has been proposed and is more or less customary to rivet or otherwise positively secure the 30 sleeve section to the filling pipe, but this has proven troublesome and unsatisfactory.

The principal object of the invention is the provision of a cap for filling tubes which conveniently can be secured in such way as to 35 prevent its removal without detection, the cap having an opening for the reception of a gauge rod, which while effective for that purpose may not be used for filling purposes.

The invention in its preferred embodiment 40 is illustrated in the accompanying drawings, wherein

Figure 1 is a perspective view of the improved cap and a portion of the filling tube, the cap-sleeve being broken away to show the 45 locking means between such sleeve and the filling tube.

Fig. 2 is a plan view of the cap-sleeve, the cap proper being removed and the filling tube being indicated in dotted lines.

Fig. 3 is a broken sectional view through the cap-sleeve and filling tube illustrating the 50 interlock between these parts.

Fig. 4 is an elevational view of the filling tube, with the cap-sleeve in broken section.

The filling tube 1, which leads to and communicates with a tank (not shown) has its upper open end suitably extended to permit convenient refilling of the tank. Its open end is provided with a cap, which must be capable of forming a complete closure to prevent unauthorized accessibility to the interior of the tank and must be further capable of permitting ready gauging of the contents of the tank at any time without thereby providing a means for unlawful replenishment of the 55 tank.

The filling cap so-called embodies a cap-sleeve designed to be screwed onto the threaded end of the filling tube and a cap proper designed to be locked to the cap-sleeve or removed therefrom at will. 60

The cap-sleeve 2 comprises a skirt portion 3, interiorly threaded for cooperation with the threaded head 4, of the filling tube, and a flange 5 at the upper end of and extending radially beyond the skirt 3. The skirt 3 is formed below the flange 5 with an offset 6, of hollow or box form and opening through the flange 5 as at 7. The outer wall 8 of the offset 6 converges towards the wall 80 of the skirt in the same direction as the threads on the filling tube and the bottom 9 of the receptacle offset inclines downwardly in the same direction. The portion of the skirt proper which forms the inner wall 85 of the offset is entirely cut away below the flange 5, so that in all applied positions of the cap-sleeve the threads on the head of the filling tube are exposed to the cavity of the offset 6. 90

The cap-sleeve 2 is formed, diametrically opposite the offset 6, with a keeper lug 10, having an elongated slot 11. The flange 5, while circular in plan, is eccentric to the upper end of the filling tube 1, in order to 95 cover and provide an entrance to the offset 6 and is provided with concentric relatively spaced locking lips 12.

The cap proper 13, comprises a flat plate 14, having a depending collar 15 to fit over the flange 5, and lugs 16 to cooperate with the locking lips 12 to secure the cap against direct separation from the cap-sleeve. The cap has a lateral keeper lug 17, formed with an opening 18, which in the final position 100 of the cap is designed to register with the keeper lug 10 of the cap-sleeve to permit the application of a lock, as 19, through the open- 105

ings 11 and 18, and thus with the cooperating lugs 16 and lips 12, positively lock the cap proper to the cap-sleeve.

In order to lock the cap-sleeve to the filling tube a ball 20 is placed in the offset 6 following the application of the cap-sleeve to the filling tube. When the cap proper is applied, the entrance to the offset is completely covered, and therefore, so long as the 10 cap proper is in place, the ball 20 is inaccessible. Any attempt to separate the cap-sleeve from the filling tube without first removing the ball 20, will cause the latter to wedge between the wall 8 of the offset and 15 the threads of the filling tube with the inevitable result of mutilating the threads and eventually rupturing the offset wall. Either result is a tell-tale of the attempt to tamper with the tank, and hence, tampering readily 20 is detectable. Evidently, the holder of the key of the lock 19, will remove the cap proper in filling the tank but, if it is necessary to remove the cap-sleeve for any purpose the cap proper first will be removed and the 25 ball 20 taken from the offset 6, when the cap-sleeve readily may be separated from the filling tube without damage to either part of the ball clutch.

Aside from means for securing the filling 30 cap against unauthorized opening it is important that the provision for gauging the contents of the tank be serviceable at all times yet without affording a medium for unlawful filling. For this purpose the cap 35 proper is equipped with a dome 21 having a gauge stick opening 22 of L form. The gauge stick 23 is of corresponding thin L section. For example, the respective wings of the gauge stick are about five-eighths 40 of an inch in width and three-thirty-seconds of an inch in thickness. With the slot 22 of an accurately fitting dimension, it is apparent that such slot, while permitting the gauging operation at any time, practically

precludes the introduction of any liquid into 45 the tank. The gauge stick is preferably of aluminum to avoid possibility of sparks in the introduction or withdrawal of the stick. A supplemental cap 24, secured to the cap-sleeve by a chain or the like 25, serves to 50 cover the dome 21 and gauging slot when desired.

The improved cap for the filling tube of fuel or like tanks is so constructed that when the cap proper is in position on the cap-sleeve and locked, the tank is positively closed against the unauthorized introduction of any liquid, as any attempt to remove the cap through removal of the cap-sleeve will result in such mutilation and rupture of the 55 parts as to advertise such unauthorized attempt. The connection between the cap-sleeve and filling tube, however, is such that the cap-sleeve may be disconnected from the filling tube after removal of the cap proper 60 and the further removal of the ball 20 from the offset 6.

Having described my invention, I claim:

1. A cap for filling tubes including a sleeve having threaded connection with the tube, 70 said sleeve being formed with an offset, a clutch operating in said offset and serving to prevent disconnection of the sleeve and tube, and a cap proper removably engaging the sleeve and covering said offset, said cap 75 proper closing the end of the tube.

2. A cap for filling tubes including a sleeve designed to be threaded onto the end of the tube and formed with an offset, a ball loosely arranged in said offset, the outer wall of 80 the offset cooperating with the ball to cause it to operate as a wedge to prevent relative movement of the sleeve and tube in one direction, a cap proper interlocking with the sleeve and overlying and closing the offset, and 85 means for locking the cap to the sleeve.

In testimony whereof I affix my signature.
ANTON JONCHA.
